UNITED STATES PATENT OFFICE.

CALVIN R. DAVIS, OF SOUTH BEND, INDIANA, ASSIGNOR TO OLIVER CHILLED
PLOW WORKS, OF SOUTH BEND, INDIANA.

CLAMP.

SPECIFICATION forming part of Letters Patent No. 699,911, dated May 13, 1902.

Application filed January 25, 1902. Serial No. 91,242. (No model.)

To all whom it may concern:

Be it known that I, CALVIN R. DAVIS, a resident of South Bend, in the county of St. Joseph and State of Indiana, have invented certain new and useful Improvements in Clamps; and I do hereby declare the following to be a full, clear, and exact description of the invention, such as will enable others skilled in the art to which it appertains to make and use the same.

My invention relates to an improvement in clamps, and more particularly to an improved clamp for colters and jointers, the object of the invention being to provide a clamp of this character which will permit of quick and easy adjustment of the colter or jointer and the rigid securing of the parts in proper position after adjustment.

With this object in view the invention consists in certain novel features of construction and combinations and arrangements of parts, as will be more fully hereinafter described, and pointed out in the claims.

In the accompanying drawings, Figure 1 is a view in side elevation, illustrating my improvements. Fig. 2 is a view in horizontal section of same. Fig. 3 is a view in vertical section, and Fig. 4 is an enlarged view of the clamping-bolt removed.

1 represents the ordinary beam of a plow, to which my improved clamp is secured, as will now be explained. 2 represents a metal plate forming an integral part of the clamp and perforated, as shown, for the reception of bolts 3, passed through the beam 1 and plate 2 and securing the plate rigidly to the beam by means of nuts 4, screwed onto the bolts.

If it is desired to permit adjustment of the clamp on the beam, I dispense with these bolts 3 and secure the clamp by means of a U-bolt 5, diagonally embracing the beam, passed through holes at opposite corners of plate 2 and secured against movement by nuts 6. While I have shown both forms of bolts 3 and 5, it is to be understood that only one form is necessary to secure the clamp to the beam, and both are shown for the purpose of illustrating alternatives. On this plate 2 a vertical sleeve 7 is made integral and is adapted to receive the colter or jointer

rod 8, and on the outer wall of said sleeve a horizontal housing 9 is located and is open at both ends, communicates between its ends with the interior of the sleeve, and the bore or channel of this housing is made angular, and the opening in one end thereof is also so shaped to align with the interior contour of said housing. An angular clamping-bolt 10 is adapted to be received in this housing and tapers into cylindrical shape at one end, where it projects through a circular opening in the end of the housing and is screw-threaded to receive a nut 12, adapted to move the bolt longitudinally (when the nut is turned) to clamp or release the rod 8. The inner face of the angular portion of said clamping-bolt 10 is inclined or made wedge shape, thus gradually increasing the width of the bolt from its cylindrical end to the angular end, so that as the bolt is drawn inward by nut 12 it will wedge tightly between the rod 8 and housing 9 and rigidly clamp said rod against movement and can as readily be moved in the reverse direction to release the rod when desired to change the position of the colter or jointer.

A great many slight changes might be resorted to in the general form and arrangement of the several parts described without departing from the spirit and scope of my invention, and hence I would have it understood that I do not wish to limit myself to the precise details set forth, but consider myself at liberty to make such slight changes and alterations as fairly fall within the spirit and scope of my invention.

Having fully described my invention, what I claim as new, and desire to secure by Letters Patent, is

1. A rod-clamp comprising a sleeve to receive the rod, a housing open at its ends and located in the outer face of the sleeve and communicating therewith, and a wedge adapted to be inserted at one end of said housing and project at the other and clamp the rod in the sleeve.

2. A rod-clamp consisting of a sleeve to receive the rod, a housing open at its ends and located in the outer face of the sleeve and communicating therewith, a wedge adapted to be inserted at one open end of said housing

and project at the other end, and a nut on said projecting end for moving the wedge longitudinally.

3. A clamp for a rod comprising a sleeve to receive the rod a housing open at its ends and located in the outer face of the sleeve and communicating intermediate its ends with same, the said housing having a flat inner face, an angular clamping-bolt adapted to be inserted through one end of the housing and project through the other open end, and a nut screwed onto the projecting end of said clamping-bolt.

4. A colter or jointer clamp, comprising a metal plate adapted to be secured to the beam of a plow, a sleeve integral with said plate to receive a colter or jointer supporting rod, a

housing on the sleeve, communicating therewith and having an angular bore or channel and an angular opening in one end, a clamping-bolt in said housing made angular and wedge shape throughout a portion of its length to wedge between the housing and rod, a cylindrical screw-threaded end on said bolt projecting through one end of said housing and a nut screwed onto said bolt.

In testimony whereof I have signed this specification in the presence of two subscribing witnesses.

CALVIN R. DAVIS.
